PISTON EXPANDER

David D. Williams, Omaha, Nebr.

Application November 2, 1938, Serial No. 238,367

7 Claims. (Cl. 309—12)

This invention relates to expanding devices and particularly to devices for expanding pistons for internal combustion engines and the like wherein such pistons have a split skirt.

5 It is an important object of my invention to provide a device of this character adapted to resiliently expand the skirt of pistons having said skirt longitudinally split or slotted.

10 It is another object of my invention to provide a device of this character wherein the expanding means is securely held chordally within the piston across the split or slot.

15 Another object of the invention is to provide a device of this character having rivets against which the expanding spring acts, said rivets being securely fixed in openings therefor in the skirt on opposite sides of the slot and having heads thereon for retaining the spring in place.

20 A further object of the invention is to provide simple means for locking same in adjustable positions, said device being adjustable for tension.

Still another object of the invention is to provide locking means therefore which will not injure the threads of the adjustment screw.

25 A still further object of the invention is to provide a device of one size which will fit substantially all alloy pistons thereby simplifying manufacturing and marketing of said device.

30 Numerous other objects and advantages of the invention will be apparent as it is better understood from the following description, which, taken in connection with the accompanying drawing, discloses a preferred embodiment thereof.

35 Referring to the drawing:

Figure 1 is a vertical section through a piston embodying the invention taken on line 1—1 of Figure 2.

Figure 2 is a horizontal section through a piston embodying my invention taken on line 2—2 of Figure 1.

Figure 3 is a longitudinal section taken through the expansion spring on line 3—3 of Figure 4.

45 Figure 4 is a plan view of the open end of the expansion spring.

Figure 5 is a vertical section through the adjustment and locking nut taken on line 5—5 of Fig. 6.

50 Figure 6 is a plan view of said adjusting and locking nut.

Referring more particularly to the drawing, which illustrates a preferred embodiment of the 55 invention, reference numeral 10 indicates the

piston generally having a skirt 11 which is obliquely split or slotted at 12.

My expansion device comprises a generally octagonal expansion spring 13, oppositely disposed sides 14 of which are concave and are 5 adapted to be engaged with rivets which are secured in openings in the skirt 11 on opposite sides of the slot 12. The rivets are preferably of brass or other relatively soft metal so that the ends which extend to the outside of the piston 10 will not score the walls of a cylinder in which the piston operates. The axis of each rivet is substantially radial with respect to the circumferential center of the piston and the sides of the body portion 16 of said rivets are tapered 15 inwardly toward the head with respect to the longitudinal centers of said rivets to compensate for the angularity of the axes thereof. A head 15 on each rivet retains the expansion spring from movement longitudinally of said rivets. 20

Side 17 of spring 13 is provided with an opening 18 therethrough adjacent the center thereof in which an adjustment screw 19 is received, the head of said screw having a slot for reception of a screw-driver or other instrument for 25 turning same.

The free ends 20 of the spring 13 are turned longitudinally with respect to screw 19 and are partially curved about the screw to provide greater contact surface with said screw. The 30 free end of the screw 19 is provided with a nut 21 having a diametrically extending slot 22 in one end adapted to receive the free ends 20 of the spring therein when the nut is screwed onto the screw 19. The free ends 20 of the spring, 35 when extending into the slot 20 of nut 21 retain said nut against rotation with respect to the screw 19 thereby permitting the nut to be screwed further onto the screw, which action draws the free ends 20 and side 17 toward each 40 other and causing sides 14 to be forced apart, said sides exerting separating pressure on the respective rivets thereby effecting expansion of the skirt. The pressure of spring 13 is sufficient to overcome the resiliency of the skirt under 45 normal conditions although the spring has a certain amount of inherent resiliency. Adjustment of the screw 19 effects the desired expansive pressure for proper functioning of the piston in its cylinder. 50

The slot 22 in nut 21 is so formed that as said nut is drawn onto the screw 19 the free ends 20 of the spring 13 are pressed against the screw to normally frictionally retain the screw 19 against rotation. The screw 19 is preferably 55

case hardened to prevent undue wearing of the threads which come into contact with the free ends 20 of the spring. It will be readily apparent that this device may be constructed in 5 one size which is adapted to fit substantially all sizes of pistons.

The invention is particularly adapted for use with pistons of the herein described character wherein the skirt has become worn through use 10 and is too loose in the cylinder. The expander is adjusted to expand the piston skirt to the proper size for proper operation in its cylinder.

It is thought that the invention and many of its attendant advantages will be understood from 15 the foregoing description and it will be apparent that various changes may be made in the form, construction, and arrangement of the parts without departing from the spirit and scope of the invention or sacrificing all of its material advantages, the form hereinbefore described being 20 merely a preferred embodiment thereof.

Having thus described my invention what I claim is:

1. In a device of the class described, the combination of a piston having a slotted, expansible skirt, comprising a rivet fixed in openings therefor in the skirt on opposite sides of the slot thereof, the axes of said rivets being substantially radial with respect to the circumferential center 30 of the piston, a head on the free end of each rivet, the sides of the body of said rivets being tapered inwardly toward the head with respect to the axes thereof to provide relatively parallel sides for said rivets with respect to each other, a substantially flat spring generally octagonally shaped in longitudinal cross-section and having the free ends thereof adjacent each other in substantially parallel relationship, said spring having an opening in the side opposite the free ends thereof, a screw received in said opening and received between the free ends of said spring, said free ends being laterally curved about the screw, and a nut adapted to be screwed onto said screw, said nut having a diametrical slot in one end in which the free ends of the spring are received to provide 45 frictional pressure of said free ends on the screw, said nut being retained against rotational movement on the screw by said free ends, said spring having concave portions on opposite sides of the screw, said spring being disposed between the 50 rivets which are received in the concave portions of said sides, and being retained in position by the heads of the rivets with respect to longitudinal movement on said rivets.

2. In a device of the class described, the combination of a piston having a slotted, expansible skirt with an expanding device comprising a rivet fixed in openings therefor in the skirt on opposite sides of the slot thereof, a flat spring, substantially octagonal in longitudinal cross-section and having oppositely disposed sides concave, said spring being received between the rivets and said rivets contacting the concave sides of said spring, the laterally extending side of the spring having an opening therein, a screw received in said opening and extending longitudinally of said spring, the free ends of said spring being turned longitudinally outwardly in substantially parallel relationship with said screw, said screw extending between said free ends of the spring, the latter being partially curved about said screw, a nut having a slot in one end adapted to receive the free ends of the spring therein and to effect frictional pressure of said free ends on 75 the screw when said nut is drawn onto said

screw, and a head on each rivet adapted to prevent movement of the spring longitudinally of said rivets.

3. In a device of the class described, the combination of a piston having a slotted, expansible skirt with an expanding device comprising a flat spring, substantially octagonal in longitudinal cross-section and having the free ends thereof adjacent each other in substantially parallel relationship, said spring having an opening in the side opposite the free ends thereof, a screw received in said opening and between the free ends of said spring, said free ends being laterally curved about the screw, a nut on the screw having a slot in one end in which is received said free 15 ends, a rivet on each side of the slot of the skirt, said rivets being within the piston and secured to the skirt, said spring being disposed between the rivets with the screw extending substantially longitudinally of the length of the piston, and 20 means for retaining the spring between the rivets.

4. In a device of the class described, the combination of a piston having a slotted, expansible skirt with a resilient expanding device comprising a flat spring having an opening adjacent the longitudinal center thereof, a screw received in said opening, said spring being turned longitudinally of said screw with opposite sides spaced therefrom, the free end portions of said spring 30 being in substantially parallel relationship with each other and being laterally curved partially about the screw, a nut on the screw, said nut having a slot in one end adapted to receive the free ends of the spring and impart pressure there- 35 to whereby said free ends frictionally grip the screw when the nut is drawn further onto the screw, opposite sides of the spring being simultaneously forced outwardly with respect to said screw, and a lug on each side of the slot of the 40 skirt of the piston and secured to said skirt, said spring being disposed between said lugs and adapted to exert expansive pressure thereto when the sides of the spring are forced outwardly by 45 tightening the nut on the screw.

5. In a device of the class described, the combination of a piston having a slotted expansible skirt with an expanding device comprising a flat spring having an opening adjacent the longitudinal center thereof, a screw rotatably received in 50 said opening, said spring being turned longitudinally of said screw with opposite sides spaced therefrom, the free end portions of said spring being in substantially parallel relationship with each other, with the screw received between 55 them, a nut on the screw, said nut having a slot in one end adapted to receive the free ends of the spring whereby pressure is imparted to said ends to effect a friction grip of said ends on said screw when the nut is drawn tight on said screw, 60 opposite sides of the spring being simultaneously forced outwardly with respect to the screw, and a lug on each side of the slot of the skirt and secured thereto, said lugs being within the piston, said spring being disposed between said lugs and 65 adapted to exert expansive pressure thereon when the sides of the spring are forced outwardly by tightening the nut on the screw.

6. An expanding device adapted to be operably attached to a piston having an expansible slotted 70 skirt, said device comprising a relatively flat spring substantially octagonal in longitudinal cross-section and having the free end portions adjacent each other in substantially parallel relationship, said spring having an opening in the 75

side opposite the free ends, a screw received in said opening and extending between the free end portions, the latter being laterally curved partially about the screw, and a nut on the screw, said nut having a slot in one end adapted to receive the free ends of the spring therein.

7. An expanding device adapted to be operably attached to a piston having an expansible slotted skirt, said device comprising a substantially flat spring having an opening adjacent the longitudinal center thereof, a screw operably received in said opening, said spring being turned longitudinally of said screw with opposite sides spaced

therefrom, the free end portions of said spring being in substantially parallel relationship with each other with the screw received between them, and a nut on the screw, said nut having a slot in one end adapted to receive the free end portions 5 of the spring therein, drawing the nut onto the screw being adapted to effect frictional pressure of the free end portions of the spring on the screw and simultaneously to effect outward movement of the sides of the spring with respect to 10 the screw.

DAVID D. WILLIAMS.
